UNITED STATES PATENT OFFICE

ARTHUR G. LEAKE, OF BRIDGEPORT, CONNECTICUT

DESIGN FOR A BASE FOR A PEN HOLDER STAND, PAPER WEIGHT, AND THE LIKE

Application filed June 17, 1931. Serial No. 40,241. Term of patent 3½ years.

To all whom it may concern:

Be it known that I, ARTHUR G. LEAKE, a citizen of the United States, residing at Bridgeport, county of Fairfield, State of Connecticut, have invented a new, original, and ornamental Design for a Base for Pen Holder Stand, Paper Weight, and the like, of which the following is a specification, reference being had to the accompanying drawings, forming part thereof.

Fig. 1 is a perspective view of a base for pen holder stand, paper weight, and the like, showing my new design, and

Fig. 2 is a top plan view thereof.

I claim:

The ornamental design for a base for a pen holder stand, paper weight, and the like, substantially as shown.

ARTHUR G. LEAKE.
